UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS

PICKER FOR LOOMS.

994,807.

Specification of Letters Patent. Patented June 13, 1911.

Application filed October 24, 1907. Serial No. 399,055.

To all whom it may concern:

Be it known that I, WILLIAM WATTIE, a citizen of the United States, residing at Worcester, in the county of Worcester and 5 State of Massachusetts, have invented certain new and useful Improvements in Pickers for Looms, of which the following is a specification.

My invention relates to a picker combined 10 with a picker stick used in looms, for picking or throwing the shuttle across the lay, and my invention particularly relates to pickers used on heavy looms, where the picking or throwing of the shuttle requires 15 more power, and the wear and tear of the picker is very great.

The picker as ordinarily made, consists of 20 a number of leather strips compressed and riveted together, with an opening for the picker stick to pass through. Either end of the picker may be used for engaging and throwing the shuttle. The engagement of 25 the shuttle with the end of the picker causes the end of the picker to be dented or depressed by the point of the shuttle, and to be worn, so that the picker soon becomes of no value.

The object of my invention is to provide 30 a picker, preferably a double end picker, of improved construction which will not be injured by the shuttle and will last longer.

In my improvements I combine with the double end picker, a piece or plug of hard 35 wood, or other suitable non-yielding material preferably of cylindrical shape, which is driven into a hole through the picker, at each end thereof, where the picker engages the shuttle.

My invention consists in certain novel 40 features of construction of my improvements in a picker, as will be hereinafter fully described.

Referring to the drawing:—Figure 1 is a front view of a picker embodying my improvements, looking in the direction of arrow *a*, Fig. 2. Fig. 2 is a top view of the picker shown in Fig. 1, looking in the direction of arrow *b*, same figure. A portion 45 of the picker at the right hand end is partially broken away, and, Fig. 3 is a section, on line 3, 3, Fig. 1, looking in the direction of arrow *c*, same figure.

In the accompanying drawing, 1 is a double end picker made of a number of 50 strips of leather, or other suitable material,

which are compressed and riveted together at each end, in this instance by two pairs of rivets 2, having the head 2' on one end and washers 3 on their other end. An opening 4 is made through the leather strips to 50 loosely receive the picker stick not shown. The opposite sides of said opening are preferably of curved shape, as shown in Fig. 1.

Through each end of the picker a transverse opening or hole is made, and into each 65 opening is driven a piece or plug 5, of wood, or other hard or non-yielding material, preferably of cylindrical shape. The plugs 5 will be held in position by the elasticity 70 of the leather of which the picker is made.

In using the picker of my improved construction, the contact of the point of the shuttle with the end of the picker, will form a recess or depression in the leather at the ends of the picker, and this depression will 75 in time extend to the wooden plug 5, as shown by dotted lines 1', Fig. 1. The wooden plug 5 being harder than the leather will resist the point of the shuttle, and when in time the wooden plug becomes worn, it 80 can be easily replaced by a new plug, and the leather portion of the picker will not be damaged.

The advantages of my improvements will 85 be readily appreciated by those skilled in the art.

A picker of ordinary construction can readily be provided with my improvements, and a picker having my improvements will 90 last much longer than the ordinary picker and give more satisfactory results.

Having thus described my invention, what I claim as new and desire to secure by Letters Patent is:

1. An improved article of manufacture, 95 a double end picker for a loom, comprising strips of leather or other suitable material having an opening therethrough to loosely receive the picker stick, two pairs of rivets at each end, to secure the strips together, 100 said strips also having an opening therethrough, near each end, extending in a plane at right angles to the plane of the first mentioned opening, a piece of wood or other non-yielding material extending 105 through the opening at each end, and enclosed by said strips on the engaging end of the picker.

2. An improved article of manufacture, 110 a double end picker for a loom, comprising

strips of leather or other suitable material, having an opening therethrough to loosely receive the picker stick, two pairs of rivets at each end to secure the strips together, 5 said strips having a circular opening there-through, near each end, extending in a plane at right angles to the plane of the first mentioned opening, a piece of wood or

other non-yielding material of cylindrical shape, extending through the opening at 10 each end, and inclosed by said strips on the engaging end of the picker.

WILLIAM WATTIE.
